UNITED STATES PATENT OFFICE.

FRANKLIN S. MCKENNEY, OF DETROIT, ASSIGNOR OF ONE-HALF TO J. M. LONGYEAR, OF MARQUETTE, MICHIGAN.

DESIGN FOR A BUTTON-FASTENING.

SPECIFICATION forming part of Design No. 25,206, dated March 3, 1896.

Application filed December 9, 1895. Serial No. 571,592. Term of patent 14 years.

To all whom it may concern:

Be it known that I, FRANKLIN S. MCKENNEY, a citizen of the United States, residing at Detroit, county of Wayne, State of Michigan, have invented and produced a new and original Design for a Button-Fastening; and I declare the following to be a full, clear, and exact description of the same, reference being had to the accompanying drawings, which form a part of this specification.

In the drawings, Figure 1 is a view in perspective of my fastening, showing the prongs projecting upward. Fig. 2 is a plan view of the head on the side opposite the prongs. Fig. 3 is a reverse plan view from that shown in Fig. 2.

My fastening has a head A and two prongs *a a.*

The leading feature of my design consists of an elongated head, the main portion *a'* of which is convoluted at each end thereof, the portions *a² a²* of the head toward the base of

the prongs being curved or coiled inward toward the center of the fastening, the head between the two convoluted portions having 25 the appearance of a single connecting-strand. The extremities of the metal from which the fastening is made, after being so shaped, are bent at substantially right angles to the head to form the prongs, as shown. A marginal 30 flange or border is formed entirely about the base of each of the prongs, the base of the prongs being entirely within the contour of said flange.

What I claim is—

The design for a button-fastening, substantially as herein shown and described.

In testimony whereof I sign this specification in the presence of two witnesses.

FRANKLIN S. MCKENNEY.
